UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING MACHINE.

Application filed October 24, 1921. Serial No. 509,980.

My invention relates to mining machines, and one of its objects is the provision of improved and efficient mechanism for digging into and splitting material from a mine 5 vein by a continuous forward rectilinear movement.

A further object of the invention is the provision of improved hydraulic power transmitting mechanism particularly adapted to the operation of coal splitting tools 10 although it may have a general application.

A further object of the invention is the provision of hydraulic anchoring and controlling apparatus for mining apparatus.

Other objects of the invention will appear hereinafter, the novel features and combinations being set forth in the appended claims.

Referring to the accompanying drawings, 20 Fig. 1 illustrates my invention embodied in a coal mining machine, the machine being shown partly in side elevation and partly in central longitudinal sectional elevation;

Fig. 2 is a plan view of the mining machine partly in section;

Fig. 3 is a sectional end elevation of a portion of the anchoring mechanism taken on the line 3—3 of Fig. 1, looking in the direction of the arrows;

Fig. 4 is a section of a portion of Fig. 2 on the line 4—4, looking in the direction of the arrows;

Fig. 5 is a sectional elevation on the line 5—5 of Fig. 2, looking in the direction of the arrows except that the parts have been arranged diagrammatically for the sake of simplicity;

Fig. 6 is a plan view of the hydraulic jack mechanism adapted to be connected to the rear end of the mining machine shown in Figs. 1 and 2; and

Fig. 7 is a central sectional elevation of the hydraulic jack mechanism shown in Fig. 6.

Referring to Fig. 1 it will be seen that the base frame 8 is adapted to rest on and slide over the mine floor. Mounted on this base frame is a large cylinder 9, in which is located a plunger 10 having a semi-spherical bottom. The upper end of the plunger 10 is provided with a recess 11 to receive the lower support 12 of the roof shoe 13, which is serrated at 14 on its upper surface. By means of the valve 15 the supply pipe 16

may be connected to the port 17 to direct 55 hydraulic pressure in the cylinder 9 beneath the plunger 10 to force the shoe 13 against the roof of the mine chamber to securely anchor the cylinder 9 and the base frame 8 in fixed immovable position. By moving 60 the lever 18 to the position shown in Fig. 1 the port 17 may be connected to the exhaust pipe 19 so that the plunger 10 will automatically descend to the position shown in Fig. 1 to effect lowering of the shoe 13 away 65 from the roof of the mine chamber.

While the part 9 is provided with a cylindrical opening to constitute the cylinder of the hydraulic roof jack, the outer contour 20 may be square in plan view as shown in Fig. 2, so as to receive the plate 21 shaped to fit the outer surface of the frame 9 and slide up and down thereon. The plate frame 21 is secured at 22 and 23 to the main frame 24 of the mining machine. Within the main frame 24 is a horizontal cylindrical opening 25 to form a hydraulic cylinder. Movable in this cylinder 25 is a plunger 26, which has a semi-spherical inner end to fit the semi-spherical inner end of the cylinder 25, as 80 shown in Fig. 1.

Rigidly secured to the plunger 26 is a supplemental mining machine frame 28, to which are connected the dislodging tools 29, 30 and 31. The intermediate dislodging tool 30 may extend forward in advance of the floor and roof dislodging tools 29 and 31 as shown in Fig. 1. While the dislodging tools 29 and 30 are preferably rigidly attached to the supplemental frame 28 so as to move bodily therewith, the uppermost dislodging tool 31 is preferably pivoted at 32 to the supplemental frame 28 so as to be adjustable in elevation.

A hydraulic cylinder 33 is secured to the supplemental frame 28 and provided with a piston 34, the piston rod 35 of which is extended upwardly as shown in Fig. 1. A link 36 is pivotally connected between the upper end of the plunger 35 and the arm 37 carrying the dislodging tool 31. By means of the valves 38 and 39 the dislodging tool 31 may be adjusted in elevation and locked rigidly in adjusted position.

A tertiary frame 40 is secured at 41 to a 105 plunger 42, which extends into the cylindrical opening 43 in the plunger 26. Connected rigidly to the supplemental frame 28 so as

to move bodily therewith are rearwardly extending arms 44 and 45, the rear ends of which are connected by the cross piece 46 extending under the main frame 24. At the 5 rear end of the arm 45 is a floor jack 47, and at the rear end of the arm 44 are the roof jack 38 and the floor jack 49, as shown in Figs. 2 and 5.

By referring to Fig. 5 it will be seen that 10 by means of the valve 50 the supply pipe 51 may be connected to the hydraulic jack 47 so as to lift the arm 45 and the cross piece 46. By connecting the valve 50 to the exhaust 15 52 these parts may be lowered. By means of the valve 53 the roof jack 48 may be operated, and by means of the valve 54 the floor jack 49 may be operated.

It should be noted that the inner plunger 42 is provided with a central longitudinal 20 passageway 55, which communicates with the cylinder 43 and extends forwardly to communicate with a passageway 56 in the tertiary frame 40. The latter is rigidly connected to the main mining machine frame 24, 25 however, so that the passageway 56 may have direct communication with the passageway 57 leading to the valve 58. When this valve is in the position shown in Fig. 1 communication is established between the supply pipe 59 and the passageway 60 which leads to the righthand end of the cylinder 25. At the same time the passageway 57 is connected through the valve 58 to the exhaust port 61. It will thus be seen that when 30 the valve 58 is in the position shown in Fig. 1 the plunger 26 will be moved toward the left to give the dislodging tools rectilinear movement to dislodge material from the mine wall, while the anchored frame 9 acts as a rigid abutment. When the plunger 26 moves toward the left the plunger 42 remains stationary and the liquid within the cylinder 43 is forced out through the passageways 55, 35 56 and 57 to the exhaust port 61. During this operation the floor jacks 47 and 49 may be locked in adjusted position and the roof jack 48 locked in released position.

During the operation of the dislodging mechanism the valve 62 may occupy the position shown in Fig. 1, so as to cause the hydraulic plunger 63 to act as a brake on the frame 9 to prevent the main frame 24 from sliding up or down out of its adjusted position on the frame 9.

After the dislodging tools have made a forward stroke in accordance with the forward stroke of the plunger 26, the valve 15 55 may be moved to the position shown in Fig. 1 so as to effect the release of the anchoring jack 13. The main frame 24 together with the rear anchoring jack may then be moved forward to a new position by opening the valve 58 so that the supply pressure pipe 59 will be connected to the passageway 57 and 60 the pipe 60 connected to the exhaust 61.

Now by retaining the roof jack 48 in anchored position so as to hold the arms 44 and 45 together with the supplemental frame 28 to which they are attached, in stationary position, the supply pressure exerted through the passageway 55 into the cylinder 43 will cause the plunger 42 to be moved toward the left and carry with it the main frame 24 and the base frame 8, together with the parts mounted on the latter. After this adjustment has been made the parts will be restored to the relative positions shown in Fig. 1, whereupon the roof jack 48 may be released and the plunger 10 moved upwardly to anchoring position. During the operation of the dislodging mechanism the plungers 64 and 65 of the floor jacks 47 and 49 may act as guides to maintain the dislodging tools at the proper elevation.

In order to facilitate the adjustment of 85 the dislodging tools to various elevations in accordance with the inclinations of the mine vein, I prefer to shape the lower surface of the frame 9 so as to have the form of the segment of a cylinder fitting a corresponding surface 66 of the base frame 8, as shown in Figs. 1 and 3. Arcuate guideways are provided at 67 and 68 by means of flanged plates secured to the base frame 8, as shown in Fig. 3. It will thus be seen that when the hydraulic plungers 64 and 65 are operated to lift or lower the supplemental frame 28, the frame 9 is free to slide on the arcuate surface 66 when the roof jack 13 is released. The bowl-shaped bottom 12 of the shoe 13 resting in the dish-shaped recess 11 in the upper end of the plunger 10, permits automatic adjustment of the shoe 13 when the main frame 24 is tilted upwardly or downwardly in accordance with the desired changes in direction of the path of travel of the mining machine in its entirety.

In order to move the entire mining machine shown in Fig. 1 more quickly over the mine floor to its desired location, the hydraulic transporting mechanism shown in Figs. 6 and 7 may be connected at 69 to the rear end of the base frame 8. The floor jacks 64 and 65 may be operated to lift the dislodging mechanism so that it will have sufficient clearance for free movement over the mine floor and the uppermost dislodging tool 31 may be moved to its lower position by operating the hydraulic motor 33. Both the roof jack 48 and the roof jack 13 may be in their released positions. The connection to the ears 69 may be detachable as by means of the pin 70, as shown in Fig. 7.

The frame 71 is provided with a longitudinal cylindrical opening 72 to form the cylinder for receiving the hydraulic plunger 73, having a semi-spherical right hand end portion to fit the corresponding bottom of the cylinder 72. The plunger 73 is rigidly

connected to a roof jack 74 comprising a floor shoe 75, a cylinder 76, a plunger 77, and a roof shoe 78.

Extending rearwardly from the frame 71 is a frame 79, which carries a rear abutment 80 adapted to engage a mine wall for an anchorage when desired.

Extending forwardly from the abutment 80 is a plunger 81, which fits into the cylinder 82 on the interior of the plunger 73.

By means of a valve 83 the supply pipe 84 may be connected to the passageways 85 and 86 to simultaneously move the frame 71 to the right and the plunger 77 upwardly.

When the lever 87 is in the position shown in Fig. 7, supply pressure will be exerted to operate the roof jack 74 to anchor the plunger 73 in fixed position. Pressure will be exerted at the right hand end of the plunger 73 to move the cylinder 71 to the right, and when the latter is connected to the mining machine shown in Fig. 1 the latter in its entirety may be transported along the mine wall. When the cylinder 71 reaches the limit of its right hand movement as viewed in Fig. 7, the roof jack 74 will be struck by the abutment 80 and the movement of the cylinder 71 limited. If the valve 87 is shifted a quarter turn to the right the supply pipe 84 will be connected to the passageway 88, which communicates with the passageway 89 extending through the center of the plunger 81 into the cylinder 82. At the same time the passageways 86 and 85 will be connected to the exhaust pipe 90.

The roof jack 74 will therefore be released and the pressure exerted in the cylinder 82 will move the plunger 73 and the roof jack 74 toward the right, the weight of the mining machine shown in Fig. 1 being sufficient to permit forward shifting movement of the roof jack 74 of relatively less weight. After the roof jack 74 has been shifted toward the right so as to occupy the relative position shown in Fig. 7, the lever 87 may again be moved to the left so as to effect another forward transporting movement of the mining machine shown in Fig. 1.

While the main purpose of the structure shown in Fig. 7 is to transport the mining mechanism shown in Fig. 1, to new operating positions, it should be noted that such transporting mechanism may also be used to assist the roof jack 9, 10, 13 in holding the base frame 8 and the frame 24 stationary. After the roof jack 13 has been anchored the roof jack 74 may be brought up to the position shown in Fig. 7 and also anchored, so that during the operation of the dislodging tools 60 the resisting abutment will be multiple, thus serving to more firmly hold the frame 24 in stationary position particularly under those conditions where the roof jack 13 alone might tend to slip along the roof and floor.

The greater the back pressure on the roof jack 74, the greater will be the fluid pressure exerted on the parts 75 and 78 of the roof jack shown in Fig. 7. Therefore, when the mineral to be mined is very hard, both roof jacks 13 and 74 may be connected in tandem and both operated to anchored position to hold the frame 24 stationary during the operation of the dislodging mechanism.

Obviously those skilled in the art may make various changes in the details and arrangement of the parts without departing from the spirit and scope of my invention as defined by the claims hereto appended, and I wish therefore not to be restricted to the precise construction herein disclosed.

Having thus fully described my invention and illustrated an embodiment thereof, what I desire to secure by Letters Patent of the United States, is:

I claim:

1. In a mining machine, the combination with a base frame adapted to rest on a mine floor, of a roof jack mounted thereon for sliding adjustment along arcuate lines, dislodging mechanism, a supporting frame carrying said dislodging mechanism and connected to said roof jack, means for adjusting the position of said dislodging mechanism by moving said supporting frame and said roof jack arcuately relatively to said base frame, and means for operating said dislodging mechanism while said roof jack and said base frame are anchored to act as an abutment.

2. In a mining machine, the combination with a supporting frame, of dislodging mechanism mounted thereon, a base frame having an arcuate support on its upper side, a roof jack having a lower arcuate surface fitting the upper side of said base frame, and means for operating said dislodging mechanism after said roof jack automatically adjusts itself on said base frame and has been anchored to serve as an abutment.

3. In a mining machine, the combination with a main frame, of means for anchoring the same, dislodging mechanism comprising claw-like spaced-apart penetrating tools adapted to penetrate the coal in its native bed and split the same from a mine vein over a wide area extending from the floor to the roof of the mine chamber, and concentric hydraulic motors one for operating the said tools and the other for moving the main frame forward to a new location.

4. In a mining machine, the combination with a main frame, of means for anchoring the same, a supplemental frame, additional anchoring mechanism for said supplemental frame, dislodging mechanism mounted on said supplemental frame to move bodily therewith, and hydraulic motor mechanism comprising concentric plungers for effecting

the operation of said dislodging mechanism and the movement of the main frame to new operating positions.

5. In a mining machine, the combination with a main frame, of means for anchoring the same, a supplemental frame, additional anchoring mechanism for said supplemental frame, dislodging mechanism mounted on said supplemental frame to move bodily therewith, a hydraulic motor comprising a cylinder on said main frame, a plunger on said supplemental frame for moving the latter forward to operate said dislodging mechanism when said main frame is anchored and said supplemental frame is not anchored, and a supplemental hydraulic motor comprising an additional plunger concentric with said first-named plunger and movable within the same to effect forward movement of said main frame when the latter is not anchored and while said supplemental frame is anchored.

6. In a mining machine, the combination with a base frame adapted to rest on and slide over a mine floor, of a standard mounted on said base frame for arcuate adjustments relatively thereto, a main frame mounted on said standard for adjustment in elevation relative thereto, means for supporting said main frame at adjusted elevation, a supplemental frame, dislodging mechanism mounted on said supplemental frame and comprising a claw-like penetrating tool adapted to enter the coal in its native bed and split the same from the mine vein over a wide area, and means for moving said supplemental frame relatively to said main frame to effect feeding of such dislodging mechanism.

7. In a mining machine, the combination with an upright standard, of a hydraulic roof jack for anchoring said standard, a main frame slidable up and down on said standard, a plurality of hydraulic floor jacks for adjusting the elevation of said main frame on said standard, a supplemental frame, dislodging mechanism mounted on said supplemental frame to move bodily therewith, and hydraulic motor mechanism between said main and supplemental frames to effect feeding of said dislodging mechanism while said standard remains anchored to form an abutment for said main frame.

8. In a mining machine, the combination with a base frame, of an upright standard mounted on said base frame for adjustment in inclination relatively thereto, a main frame mounted on said standard and adjusted in elevation relatively thereto, a supplemental frame, dislodging mechanism mounted on said supplemental frame, means for moving said supplemental frame relatively to said main frame to effect feeding of said dislodging mechanism, and means for tilting said main frame together with said

standard on said base frame to vary the feeding path of travel of said dislodging mechanism.

9. In a mining machine, the combination with a base frame having an upper surface of the shape of a segment of a cylinder, of an upright standard having a lower surface fitting the upper surface of said base frame and guided to slide relatively to said base frame to vary the elevation of said standard, a hydraulic roof jack for anchoring said standard and said base frame, a main frame connected to said standard and extending approximately horizontally therefrom, a supplemental frame connected to said main frame for movement relatively thereto, dislodging mechanism mounted on said supplemental frame to move bodily therewith, means for moving said supplemental frame relatively to said main frame while said standard and said base frame are anchored to act as an abutment for said main frame, and means for varying the elevation of the dislodging mechanism by tilting said main frame and said standard on said base frame.

10. In a mining machine, the combination with an upright standard, of a main frame connected thereto for up and down movement thereon, a hydraulic brake for holding said main frame at adjusted elevation, a supplemental frame, dislodging mechanism stationary relative to said supplemental frame to move bodily therewith, hydraulic motor mechanism for moving said supplemental frame to effect feeding of said dislodging mechanism, and hydraulic floor jack mechanism for varying the elevation of said main frame on said standard.

11. In mining apparatus, the combination with an upright standard, of a roof jack for anchoring said standard, a hydraulic motor connected to said standard and extending horizontally therefrom and comprising a cylinder and a hollow plunger, a supplemental plunger rigidly connected to said cylinder and adapted to extend into and slide in said hollow plunger, and means for controlling the relative movements of said plungers and said cylinder to effect transleading movements of said plungers alternately.

12. In mining apparatus, the combination with a main frame, of a supplemental frame claw-like dislodging mechanism mounted on said supplemental frame to move bodily therewith in position to penetrate the coal in its native bed and split the same from the mine vein over a wide area, a cylinder connected to one of said frames, a plunger secured rigidly to said cylinder, a combined supplemental cylinder and plunger rigidly connected to the other frame and fitting into said first-named cylinder and adapted to receive said plunger, and means for operating said plungers to secure a translating movement of either plunger while the other re-

main stationary to secure feeding of said dislodging mechanism or re-positioning of the main frame.

13. In a mining machine, the combination with a main frame, of a supplemental frame, dislodging mechanism mounted on said supplemental frame to move bodily therewith and comprising a claw-like penetrating tool adapted to penetrate the coal in its native bed and split the same from the mine vein over a wide area, and fluid pressure mechanism comprising concentric plungers for effecting the operation of said dislodging mechanism.
14. In a mining machine, the combination with supporting framework, of dislodging mechanism mounted thereon comprising claw-like penetrating means adapted to enter the upright face of a mine vein and split the mineral therefrom over a wide area, and fluid pressure mechanism comprising concentric plungers for effecting the operation of said dislodging mechanism.

15. In a mining machine, the combination with a main frame, of a supplemental frame, dislodging mechanism mounted on said supplemental frame to move bodily therewith, a fluid pressure motor comprising a cylinder on said main frame, a plunger on said supplemental frame for moving the latter forward to operate said dislodging mechanism, and a supplemental fluid-pressure motor comprising an additional plunger concentric with said first-named plunger and movable within the same to effect forward movement of said main frame while said supplemental frame is stationary.

16. In a mining machine, the combination with an upright standard, of hydraulic mechanism for anchoring said standard, a main frame adjustable in elevation on said standard, means adapted to engage the floor for adjusting the elevation of said main frame on said standard, a supplemental frame, dislodging mechanism mounted on said supplemental frame to move bodily therewith, and motor mechanism between said main and supplemental frames to effect feeding of said dislodging mechanism while said standard remains anchored to form an abutment for said main frame.

17. In a mining machine, the combination with supporting framework, of dislodging mechanism mounted thereon, means comprising fluid pressure concentric cylinders for operating said dislodging mechanism, and means for positioning said framework, said positioning means comprising an anchoring jack connected to said fluid pressure concentric cylinders.

18. In a mining machine, the combination with an abutment comprising a roof jack, of dislodging mechanism, a frame pivoted to said abutment for lateral adjustment on an upright axis, said frame carrying said dis-

lodging mechanism, means for operating said dislodging mechanism by pushing the latter along rectilinear lines from said abutment, and a fluid-pressure motor connected to said abutment to move the same together with said frame and said dislodging mechanism along horizontal lines to adjust the position of the dislodging mechanism.

19. In a mining machine, the combination with a supporting frame, of dislodging mechanism thereon confined to rectilinear movements in its operation, a roof jack to serve as an abutment for said frame, means for operating said dislodging mechanism when said roof jack is in anchored position, fluid-pressure mechanism pivotally connected to said abutment for adjusting the position of the latter and said dislodging mechanism, and an additional roof jack to serve as an abutment during the operation of said fluid pressure mechanism.

20. The combination with a mining machine, of an abutment comprising a frame adapted to rest on and slide over a mine floor with a roof jack mounted thereon, and positioning means pivotally connected to said abutment and comprising an additional roof jack connected to concentric fluid pressure cylinders.

21. In a positioning means for mining machines, the combination with a main frame adapted to be connected to the mining machine, of a cylinder on said main frame, a cylinder plunger movable into said cylinder, a roof jack connected to said cylinder plunger, an additional plunger movable into said first-named plunger, a frame for pivotally connecting said additional plunger to said main frame, and means for controlling the application of fluid pressure to said roof jack and in said cylinders and plungers to effect forward movement of the main frame and the mining machine to which it is connected when said last-named roof jack is anchored and to cause said second-named frame to move said roof jack forwardly when released.

22. In positioning mechanism for mining machines, the combination with a main frame adapted to be connected to a mining machine, of a cylinder on said main frame, a loop extension from said main frame, a hydraulic jack extending to said loop extension, a cylinder connected rigidly to said first-roof jack and extending into said first-named cylinder as a plunger, an additional plunger rigidly connected to said loop extension and fitting into said second-named cylinder, and a valve for controlling the control of the fluid pressure medium to effect forward movement of the first-named frame when the roof jack is anchored and to cause said loop extension to move the roof jack forward when the latter is released.

23. In a mining machine, the combination

with a main frame, of a supplemental frame mounted thereon for movement relatively thereto, dislodging mechanism mounted on said supplemental frame for movement bodily therewith, spaced-apart fluid pressure floor jacks connected to said supplemental frame in position to adjust the elevation of both frames and guide the movement of the supplemental frame along the floor relatively to said main frame, a roof jack on said supplemental frame, fluid pressure mechanism between said main and supplemental frames for effecting the operation of said dislodging mechanism when said roof jack is released and to effect forward movement of the main frame to a new position when said roof jack anchors said supplemental frame.

24. In a mining machine, the combination with a supporting frame, of a roof jack adapted to act as an abutment, dislodging mechanism mounted on said frame and confined to rectilinear movements during operation, said dislodging mechanism being dependent for its operation on the anchoring of said abutment, means for operating said dislodging mechanism along rectilinear lines when said abutment is anchored, a base frame having an upper recess in the shape of a segment of a cylinder to receive the correspondingly shaped bottom of said frame to permit adjustment in elevation of said dislodging mechanism, and fluid-pressure motor apparatus connected to said frame to position the abutment when the latter is released.

25. In mining apparatus, the combination with a supporting frame, of an abutment connected thereto and adapted to be anchored, dislodging mechanism on said frame confined to rectilinear movements during operation, said dislodging apparatus being dependent for its operation on the anchoring of said abutment, and fluid-pressure apparatus pivotally connected to said abutment for positioning the latter and said frame when said abutment is released from its anchored position.

26. A mining machine comprising a supporting frame, an abutment connected to said frame and adapted to be anchored in a mine chamber, dislodging mechanism mounted on said frame to operate by rectilinear movement against the action of said abutment, said dislodging mechanism being dependent for its operation on the anchoring of said abutment, additional anchoring mechanism adapted to rest by its own weight on a flat floor and be projected against the roof of the mine chamber to form another abutment distant from said first-named abutment but connected in tandem to the latter, powerful propelling mechanism comprising a longitudinally extending horizontal fluid-pressure motor connected between said abut-

ments, and means connected between said motor and said additional anchoring mechanism to cause the latter to be anchored more firmly when said propelling mechanism meets with greater resistance in moving to a new location said first-named abutment and said frame.

27. In a mining machine, the combination with a supporting frame, of a fluid-pressure operated anchoring device, dislodging mechanism mounted on said frame, an additional fluid-pressure operated anchoring device, fluid-pressure propelling mechanism comprising a hollow piston serving to connect both of said anchoring devices in tandem, a fluid passageway extending through said hollow piston from said fluid-pressure propelling mechanism to said additional anchoring device, and means for supplying a fluid-pressure medium to said additional anchoring device and to said propelling mechanism simultaneously to effect movement of said frame and said first-named anchoring device together with said dislodging mechanism.

28. In a mining machine, the combination with a supporting frame, of a fluid-pressure operated anchoring device adapted to form an abutment, dislodging mechanism adapted to operate by rectilinear movement along the mine wall and dependent for its operation on the anchoring of said abutment, an additional fluid-pressure operated anchoring device adapted to form an additional abutment, a fluid-pressure motor comprising a cylinder and a piston connecting said abutments in tandem, said piston having a fluid passageway extending therethrough to said first-named fluid-pressure operated anchoring device, an operating connection between said piston and said additional abutment, and means to establish direct communication between said cylinder and said additional fluid-pressure operated anchoring device through the passageway in said piston and said operating connection and to effect re-positioning of said frame together with said dislodging mechanism and said first-named abutment.

29. In a mining machine, the combination with a supporting frame, of an abutment therefor, dislodging mechanism mounted on said frame for rectilinear operation along a mine wall, said dislodging mechanism being dependent for its operation upon the anchoring of said abutment, a fluid-pressure operated anchoring device adapted to form an additional abutment, a fluid-pressure motor connecting said abutments in tandem and comprising a hollow piston with a fluid passageway extending along the walls thereof, an operating connection between said piston and said additional abutment, and means for connecting the fluid passageway in said piston to the fluid-pressure chamber of the

fluid-pressure operated anchoring device to effect re-positioning of said frame together with said dislodging apparatus and said first-named abutment.

30. In a mining machine, the combination with a supporting frame, of an abutment therefor, dislodging mechanism mounted on said frame for rectilinear operation, a supplemental frame connected to said first-named frame, a fluid-pressure operated anchoring device mounted on said supplemental frame and adapted to form an abutment therefor, a fluid-pressure motor connecting said abutments in tandem and comprising a cylinder with a piston movable within said cylinder, and a fluid-pressure passageway extending from said cylinder through said piston to the fluid-pressure chamber of said fluid-pressure anchoring device to establish fluid-pressure communication between said cylinder and the fluid-pressure chamber of the anchoring device to effect anchoring of said abutment on the supplemental frame and the operation of said motor to move the first-named frame and its abutment together with said dislodging mechanism to a new location.

31. In a mining machine, the combination with a main frame, of an abutment therefor, dislodging apparatus mounted on said frame, a supplemental frame pivotally connected to said main frame for lateral adjustment of the dislodging apparatus on an upright axis to various angular positions relative to said main frame, a fluid-pressure operated anchoring device adapted to form an abutment for said supplemental frame, a fluid-pressure operated motor on said supplemental frame and having passageways connected directly to said fluid-pressure operated anchoring device, and means for simultaneously controlling the operation of said fluid-pressure operated anchoring device and the operation of said motor to cause said anchoring device to act as an abutment for said motor and to cause said motor to move the main frame together with its abutment and said dislodging apparatus to a new position.

32. In mining apparatus, the combination with a mining machine, of a hydraulically operated roof jack to serve as an abutment therefor, an additional hydraulically operated roof jack spaced behind said first-named roof jack in tandem therewith, hydraulically operated motor mechanism connecting said roof jacks in tandem and serving to advance the machine when said first-named roof jack is released, said second-named roof jack comprising a cylinder and said motor mechanism comprising a piston within a cylinder and the latter being a piston within another cylinder, connections

comprising a fluid-pressure passageway to effect a variation of pressure used to operate said second-named roof jack in accordance with the pressure for operating the advancing mechanism, and means for controlling the operation of said motor mechanism to secure advancing of either the mining mechanism or the second-named roof jack.

33. In mining apparatus, the combination with a mining machine, of an abutment therefor, a second abutment spaced from the first-named abutment, a fluid-pressure operated motor between said abutments, said motor comprising a piston within a cylinder which serves as a piston within another cylinder, the latter cylinder being connected to one of said abutments and said first-named piston being connected to the other abutment, and means for controlling said motor to advance the first-named abutment together with said mining apparatus while the second-named abutment is anchored, and to advance the second-named abutment when the first-named abutment is anchored.

34. In a mining machine, the combination with mining mechanism, of an abutment therefor, an anchor arranged to engage the floor and roof of the mine chamber, said anchor comprising an upright hydraulic cylinder and a plunger movable therein, a power device for advancing said mining mechanism together with said abutment, said power device comprising a roof jack having an additional hydraulic cylinder with a piston therein, a frame for guiding said roof jack and holding it upright when released, means for introducing fluid into said additional cylinder to operate said power device, and a permanent connection between said cylinders and extending through said piston to introduce liquid pressure into the upright cylinder from said additional cylinder and thereby increase the pressure exerted by said anchor on the floor and roof in accordance with the force exerted by said power device for advancing the mining mechanism and its abutment.

35. In a mining machine, the combination with a main frame, of a supplemental frame, dislodging mechanism mounted on said supplemental frame, a fluid-pressure motor comprising a cylinder on one of said frames, a plunger on the other frame, means for controlling said motor to operate said dislodging mechanism, and a supplemental fluid-pressure motor concentric with said first-named motor to effect advance movement of the main frame while said supplemental frame is stationary.

In testimony whereof I have signed my name to this specification on this 22d day of October, A. D. 1921.

EDMUND C. MORGAN.
